LOCK

Frank Ellison Best, Seattle, Wash., assignor to
 Frank E. Best, Inc., Seattle, Wash., a corporation of Washington

Application February 11, 1929, Serial No. 339,177

7 Claims. (Cl. 70—47)

My invention relates to improvements in locks of the lock controlled assembly type in which a lock core is secured within a receptacle by key controlled means and an object of my invention is to provide a lock of this nature having snap latch means for locking a lock core into the receptacle, said lock core being releasable by use of a key.

In my prior Patent Number 1,384,022 issued July 5, 1921, I have disclosed a lock in which a core is arranged to be both locked into and released from a core case by the operation of a key.

In this application, I disclose a lock in which a lock core is arranged to be locked into a receptacle or core case by snap latch means and can only be released therefrom by the use of a key.

Another object of the invention is to provide a pin tumbler lock of this nature which may be made in a very small size thus making it especially desirable for use on motor vehicles and for other uses where a lock of small size is required.

A further object is to provide a lock of this nature in which the usual integral head of the key plug is formed on the rear end and the head portions at the front of the key plug are secured to the key plug in the process of assembly of the lock and may be of different materials which may be finished differently for ornamental purposes.

Further objects are to provide a lock of this nature which is strong and substantial in construction, durable and efficient in operation, cheap to manufacture, easy to install within the lock receptacle and readily removable by the use of the proper key, to permit the combination to be changed.

Other and more specific objects will be apparent from the following description taken in connection with the accompanying drawing.

In the drawing Figure 1 is a view in end elevation of a lock constructed in accordance with my invention.

Figure 2 is a view of the same partly in side elevation, and partly in section on broken line 2—2 of Figure 1.

Figure 3 is a cross section through the core substantially on broken line 3—3 of Figure 4, the tumbler pins being omitted.

Figure 4 is a cross section of the core substantially on broken line 4—4 of Figure 3.

Figure 5 is a detached view in longitudinal section of the key plug and face plate for the same, showing the face plate as it may appear before

it has been applied to the key plug.

Figure 6 is a cross section substantially on broken line 6—6 of Fig. 3.

Like reference numerals designate like parts throughout the several views.

Referring to the drawing, I have shown a lock core, including a body portion of figure 8 shape in cross section, having one tubular part 6 for the reception of a cylindrical key plug 7 and sleeve 8 and having a non-tubular portion 9 which is provided with transverse holes 10 for the reception of the usual tumbler pins 11, springs 12 and caps 13.

The key plug 7 is surrounded by the sleeve 8 which fits snugly within the bore of the tubular body portion 6 and is rotatable relative to both the plug 7 and body portion 6 and said sleeve and key plug are both provided with bores 14 for reception of the tumbler pins 11, thus forming a double shear line lock in which the key plug may be turned within the sleeve when the breaks in the tumbler pins register with the shear line formed at the periphery of the key plug or in which the key plug and sleeve may be turned as a unit within the body portion 6 when breaks in the tumbler pins register with the shear line formed at the periphery of the sleeve 8.

The key plug 7 has an integral head 15 on its inner end, which may be provided with any suitable means, as a throw pin 16, for engaging with any suitable bolt or secondary lock mechanism. Said key plug is provided at its outer end with a face plate 17 which may be recessed as at 18 for the reception of a bell shaped end 19 of the key plug 1 where by the key plug 7 and face plate 17 may be secured together by a swaging process when the lock is assembled. A face 20 is also swaged or riveted onto the end of the solid portion 9 of the core body by stud means 21.

For the purpose of locking this lock core with in a suitable receptacle or housing 40 I provide a locking lug 22 which is swingingly mounted within a recess 23 in the core body 9 and is urged outwardly by a spring 24. The rear end of the locking lug 22 is provided with a tongue 25 which fits into a slot 26 and supports said locking lug for swinging movement. The rear end of the locking lug adjacent the tongue 25 abuts solidly against the wall of the core body 9. The rear end of the locking lug is cut away on the inner side to afford room for an enlargement 27 on the rear end of the spring 24, whereby the spring 24 is held in the correct position. The enlargement 27 also makes it possible to construct a spring which will withstand bending repeatedly without breaking.

For the purpose of limiting the outward swing-

ing movement of the locking lug 22 and providing a means by which said locking lug may be retracted, I provide a stop member 28 which is slidable crosswise of the locking lug by dove tail means 29 and is located on the inner side and toward the forward end of said locking lug. An offset extension 30 on one end of the stop member 23 extends downwardly into a recess 31 in the thickened upper portion 32 of the sleeve 8 and is arranged to be engaged by a portion 33 of said sleeve so that the locking lug may be retracted by turning the sleeve in a clockwise direction from the position shown in Figure 4. The recess 31 in the sleeve is large enough to permit the stop member 28 to be pressed into a fully retracted position by applying a pressure against the outside of the locking lug 22 when the tumbler pins are aligned. The length of the stop member 28 is not greater than the width of the locking lug 22 so that in assembling the device the spring 24 may first be placed in the recess 23, the locking lug 22 with the stop member 28 telescopically engaged therewith and flush at both top and bottom may then be inserted and the stop member 25 may be allowed to drop down into the recess 31 in the sleeve thus completing the assembly and making it impossible to remove the locking lug. The dropping down of the stop member 28 is aided by the spring 24 which exerts a pressure against an inclined surface 35 on said stop lug, and said spring further serves to lock the stop lug down.

The operation of this lock is similar to that of the usual pin tumbler lock in so far as its bolt operating function is concerned, the usual operating key aligning the cuts of the tumbler pins 11 on the shear line at the periphery of the key plug and permitting rotation of the key plug within the sleeve 8 while said sleeve 8 is locked against rotation. The lockcore may be quickly and easily slipped into a receptacle, the locking lug being pressed back by contact with the receptacle until the core is fully inserted and in its proper position, whereupon the locking lug 22 may snap out and lock behind a suitable shoulder 34 of the receptacle into which the core is inserted. The receptacle and the shoulder 34 are shown in Figures 3 and 6, it being understood that the form of this receptacle may be varied to suit different requirements. To retract the locking lug 22 from engagement with the shoulder 34 and thus permit the core to be withdrawn from its receptacle it is necessary to use a control key which will align the cuts in the tumbler pins 11 on the shear line formed at the outer periphery of the thickened portion 32 of the sleeve 8 thus allowing the sleeve 8 to be turned to the right within the portion 6 far enough to draw in the locking lug 22, clear of the shoulder 34.

The lock core can thus be quickly and easily inserted into its receptacle without the use of a key, the lug 22 snapping into locking engagement with the shoulder 34, but to remove said core a suitable key must be used.

The foregoing description and accompanying drawing clearly disclose what I now regard as a preferred embodiment of my invention but it will be understood that this disclosure is merely illustrative and that changes in the invention may be made within the scope and spirit of the following claims.

I claim:

1. In a lock, a receptacle, a lock core arranged to be placed within said receptacle, snap latch means for locking said lock core within said

receptacle, throw means on said lock core, and pin tumbler lock means in said lock core having two shear lines operable by different key combinations, one shear line controlling said throw means and the other shear line controlling the retraction of said snap latch means. 5

2. A lock, embodying a lock core, means forming a receptacle for said lock core, snap latch means on said lock core for locking said core within said receptacle, throw means on said lock core, and pin tumbler lock means in said lock core having two shear lines operable by different key combinations, one shear line controlling said throw means and the other shear line controlling the retraction of said snap latch means. 15

3. A lock, embodying a lock core, means forming a receptacle for said lock core, a locking lug on said lock core for locking said core within said receptacle, a spring urging said locking lug into engagement with the receptacle, throw means on said lock core, and pin tumbler lock means in said lock core having two shear lines operable by different key combinations, one of said shear lines controlling said throw means and the other shear line controlling the retraction of said locking lug whereby said lock core is released. 20

4. A lock core including a body portion having a recess in one side, a locking lug pivotally mounted for swinging movement within said recess, a spring urging said lug outwardly, said lug being free to be pressed into said recess, throw means on said lock core, and pin tumbler lock means in said lock core having two shear lines operable by different key combinations, one of said shear lines controlling said throw means and the other shear line controlling the retraction of said locking lug whereby said lock core is released for retracting said locking lug within 35 said recess. 40

5. A lock core, embodying a body portion having a recess in one side, a locking lug operable within said recess and having one end pivotally connected with the wall at the end of said recess, a spring disposed behind said locking lug for urging the non-pivoted end of said lug outwardly, means for limiting the outward movement of said locking lug and lock controlled means for retracting said locking lug. 50

6. In a lock core, a body portion having a recess in one side, a locking lug operable within said recess and pivotally retained at one end, said locking lug having transverse dovetail groove means in its inner side, a spring behind said locking lug for urging the same outwardly, a key plug rotatable within said body portion, a sleeve on said key plug, said sleeve having a recess near the location of the recess in said body portion and a stop member slidably in the dovetail groove, means in said locking lug and extending into the recess in said sleeve for limiting the outward movement of said locking lug and retracting said locking lug in response to turning of said sleeve. 60

7. In a lock core, a body portion having a recess in one side, a locking lug operable within said recess, a key plug rotatable within said body portion, a sleeve rotatable on said key plug, pin tumbler lock means within said lock core adapted for operation by a key whereby said sleeve may be rotatively moved, and locking lug operating means connecting said sleeve with said locking lug whereby said locking lug may be positioned by rotatively moving said sleeve. 70
